DESIGN FOR A WRIST-WATCH

Emanuel L. Arzt, Brooklyn, N. Y.

Application March 17, 1938, Serial No. 75,896

Term of patent 3½ years

To all whom it may concern:

Be it known that I, Emanuel L. Arzt, a citizen of the United States, residing in the Borough of Brooklyn, city of New York, county of Kings, and State of New York, have invented a new, original, and ornamental Design for a Wrist-Watch, of which the following is a specification, reference being had to the accompanying drawing, forming part thereof.

I claim:

The ornamental design for a wrist-watch as shown.

EMANUEL L. ARZT.
